UNITED STATES PATENT OFFICE.

WILLIAM M. JEWELL, OF CHICAGO, ILLINOIS.

CONTROLLER.

SPECIFICATION forming part of Letters Patent No. 653,743, dated July 17, 1900.

Application filed January 9, 1899. Serial No. 701,599. (No model.)

To all whom it may concern:

Be it known that I, WILLIAM M. JEWELL, a citizen of the United States, residing at Chicago, in the county of Cook and State of Illinois, have invented certain new and useful Improvements in Controllers, of which the following is a specification, reference being had to the accompanying drawings.

My invention relates to controllers for regulating the flow of water or other fluid through a conduit, and has for its object to provide a controller in which variation in the pressure of water in the conduit will act to enlarge or reduce the area of the discharge-passages in such manner as to maintain a substantially constant flow.

To this end my invention, generally stated, consists in providing a conduit with a movable outlet-pipe through which the water or other fluid flows in its passage from the conduit, said pipe being arranged to be moved by variation in the pressure of the water in the conduit, such movement effecting a variation of the area of the discharge ports or passages in such manner as to increase the area when the pressure in the conduit is reduced and to reduce the area when such pressure increases.

My invention further comprises means for regulating the action of the controller, so that the normal flow may be varied. It also provides means whereby under certain conditions a greater movement of the outlet-pipe is necessary to effect a given variation of the area of the discharge-ports than at other times—that is to say, where the water in the conduit is under considerable pressure the apparatus is arranged so that a greater movement of the outlet-pipe is necessary to effect a given variation in the area of the discharge-ports than when the water in the conduit is under lower pressure, this arrangement being conducive to uniformity in the flow.

My invention also comprises certain details of construction which will be hereinafter particularly pointed out.

In the drawings, Figure 1 is a vertical section. Fig. 2 is a horizontal section on line 22 of Fig. 1. Fig. 3 is a plan view of the outlet-pipe. Fig. 4 is a view of the lower end thereof looking upward, and Fig. 5 is a plan view of the head at the lower end of said pipe.

Referring to the drawings for a particular description of my invention as therein illustrated, 6 indicates a conduit or pipe having a chamber 7 communicating therewith and forming an extension thereof. The shell 8 of the chamber 7 is preferably secured to the pipe 6 by bolting it to a coupling 9, as illustrated in Fig. 1; but it may be otherwise arranged, if desired. Above the chamber 7 is a chamber 10, which communicates with a second conduit or delivery-pipe 11, as shown in Fig. 1.

12 indicates an annular flange formed in the casing 8, which flange separates the chambers 7 and 10 when the parts of the controller are assembled as illustrated.

13 indicates a cap which fits over the upper end of the casing 8 and is firmly secured thereto.

14 indicates an outlet pipe or valve which is fitted in the shell 8, its upper end fitting snugly in a flange 15 at the upper end of said shell, the intermediate portion of said outlet-pipe having a bearing in the flange 12. At its lower end the pipe 14 is provided with a peripheral flange 16, which extends to the wall of the chamber 7. The pipe 14 is longitudinally movable in the shell 8, and when in its lowermost position rests upon a flange 17, preferably formed on the coupling 9, as shown in Fig. 1. The flange 16 is provided with a number of orifices or passages 18, through which water is admitted from the conduit 6 to the chamber 7.

19 indicates a plurality of segmental blocks which project below the flange 16, being substantially continuations of the outlet-pipe 14.

20 indicates a head which fits upon the lower end of the outlet-pipe 14, bearing against the lower edges of the blocks 19, as shown in Fig. 1. The head 20 is provided with segmental blocks 21, which are adapted to fit within and bear closely against the segmental blocks 19, the blocks 19 and 21 being so arranged relatively to each other that the blocks 21 when moved to the proper position by the rotation of the head 20 close the spaces between the blocks 19. By this construction, therefore, the area of the passages 22 between the head 20 and the lower end of the outlet-pipe 14 may be varied. For the purpose of rotating the head 20 to adjust the size of the pas-

sages a rod 23 is provided, the lower end of which is connected to the head 20, its upper end being fitted in a bearing in a spider 24, as shown in Fig. 1. The upper end of the 5 rod carries a nut 25 which screws upon it and serves to hold the head 20 up in operative position, and also as a means of rotating said rod 23. Said rod also carries a pointer 26 to indicate the position of the head.

10 As shown in Fig. 1, the outlet-pipe 14 is provided with one or more ports or discharge-passages 27, arranged to communicate with the chamber 10. In the best form of my invention the ports 27 are tapered in form, being 15 of greatest width at the top and gradually diminishing in width to the bottom.

The operation of my improved controller is as follows: The water or other fluid rises through the conduit 6 and thence flows 20 around the edges of the head 20 through the passages 22 into the outlet-pipe 14, thence rising through said pipe and being discharged through ports 27 into the chamber 10, whence it flows through the delivery-pipe 11. When 25 the parts are in the position shown in Fig. 1, the ports 27 are wide open, the pressure of the water in the conduit 6 being at the lowest point. Assuming that with the segments 19 21, arranged as shown in Figs. 1 and 2, the 30 desired flow of water is provided when the pressure is at the minimum should the pressure of the water in the conduit 6 increase, the increased pressure will be partially directed against the under side of the head 20, 35 causing it to rise, raising the pipe 14 and partially closing the ports 27, inasmuch as the upper ends of said ports will pass above the lower edge of the flange 15 and be closed by it. This decrease in the area of the discharge- 40 ports 27 reduces the discharge, and consequently causes a back pressure, which neutralizes the excess of pressure in the conduit 6 beyond what is required to raise the discharge-pipe. When the pressure in the conduit 6 is reduced, the discharge-pipe 14 is 45 permitted to drop, again increasing the area of the ports 27. By this means whatever variations may occur in the pressure of the water in the conduit 6 do not materially affect 50 the flow of water through the pipe 14 and conduit 11, which is maintained at practically a constant point. When the pressure in the conduit 6 is greatly increased, the pipe 14 is raised to a higher point, as above de- 55 scribed, the wider portions of the ports 27 being closed, the water being discharged from the pipe 14 through the narrower lower portions of said ports, and, as it is evident that the pipe 14 must move a greater distance 60 when in such position in order to effect a given variation in the area of the ports 27 than is the case when it is at its lowermost position the result is that when the water is under high pressure, at which time it is more 65 subject to sudden variations, the greater movement of the pipe 14, caused by such variations in the pressure, does not materially

affect the outflow. To vary the flow, the head 20 is adjusted to vary the area of the passages 22.

When the controller is in use, water flows through the orifices 18 into the chamber 7, forming a cushion for the pipe 14, preventing violent action thereof, and causing it to move gradually when moved in either direction.

It will be understood that the specific construction above described may be varied without departing from my invention, as various modifications of the apparatus described may be made.

In the specification and claims I have used the term "outlet-pipe" in describing the part 14; but it should be understood that I do not thereby limit myself to the use of a pipe proper, as the term as therein used includes also any conduit through which the fluid is passed for the purpose of controlling its flow and by the movement of which the flow is regulated. It will also be understood that while this apparatus is intended particularly for use in controlling the flow of water, it may be used for controlling "fluids generally," by which term I mean to include gases as well as liquids.

That which I claim as my invention, and desire to secure by Letters Patent, is—

1. In a controller, the combination of a conduit, a movable outlet-pipe communicating therewith, one or more ports for the discharge of fluid from said outlet-pipe, means operated by the movement of said pipe for varying the area of said ports, and means between said ports and said conduit operated by the pressure of the fluid in the conduit for moving said pipe, substantially as described.

2. In a controller, the combination of a conduit, a longitudinally-movable outlet-pipe communicating therewith, one or more ports for the discharge of fluid from said outlet-pipe, means operated by the longitudinal movement of said pipe for varying the area of said ports, and means between said ports and said conduit operated by the pressure of the fluid in the conduit for moving said pipe longitudinally, substantially as described.

3. In a controller, the combination of a conduit, a longitudinally-movable outlet-pipe communicating therewith, a head carried by said pipe, one or more passages for permitting fluid from said conduit to pass by said head into said pipe, one or more ports for the discharge of fluid from said pipe, and means for varying the area of said ports by the longitudinal movement of said pipe, substantially as described.

4. In a controller, the combination of a conduit, a longitudinally-movable outlet-pipe communicating therewith said pipe being movable by the pressure of the fluid in the conduit, one or more tapered ports for the discharge of the fluid entering said outlet-pipe from the conduit, and means controlled by the longitudinal movement of said outlet-pipe for varying the area of said ports in-

versely as compared with the pressure of the fluid in the conduit, substantially as described.

5. In a controller, the combination of a conduit, a movable outlet-pipe communicating therewith, one or more ports for the discharge of fluid from said outlet-pipe, means for varying the area of said ports by the movement of said pipe, means operated by the pressure 10 of the fluid in the conduit for moving said pipe, and means for varying the area of the passage from said conduit to said outlet-pipe, substantially as described.

6. In a controller, the combination of a conduit, an outlet-pipe adapted to reciprocate, said pipe having segmental blocks 19 at its lower end and a head 20 fitted against the lower edges of said blocks, a rod 23, and one or more ports for the discharge of water from 20 said pipe, substantially as described.

7. In a controller, the combination of a conduit, an outlet-pipe adapted to reciprocate, said pipe having segmental blocks 19 at its lower end and a head 20 fitted against the 25 lower edges of said blocks, said head having blocks 21, a rod 23, and one or more ports for the discharge of water from said pipe, substantially as described.

8. The combination of a conduit, a casing 30 having a chamber 7, a discharge-pipe 14 in said casing, said pipe having a flange 16, said flange having passages 18, one or more ports in said pipe 14, a head 20 carried by said pipe 14, and one or more passages 22 at the lower 35 portion of said pipe, substantially as described.

9. In a controller, the combination of a conduit, a movable outlet-pipe communicating therewith, said pipe being movable by the 40 pressure of the fluid in the conduit, one or more ports for the discharge of the fluid entering said outlet-pipe from the conduit, and means controlled by the movement of said outlet-pipe for varying the area of said ports 45 inversely as compared with the pressure of the fluid in the conduit, substantially as described.

10. In a controller, the combination of a conduit, a longitudinally-movable outlet-pipe 50 communicating therewith, one or more ports for the discharge of fluid from said outlet-

pipe, means operated by the pressure of the fluid for moving said pipe longitudinally, and means operated by the fluid for cushioning said outlet-pipe, substantially as described. 55

11. In a controller, the combination of a conduit, a movable outlet-pipe communicating therewith, one or more ports for the discharge of fluid from said outlet-pipe, means operated by the pressure of the fluid for varying 60 the area of said port or ports, and means for varying the flow through said outlet-pipe independently of the pressure of the fluid, substantially as described.

12. In a controller, the combination of a 65 conduit, a longitudinally-movable outlet-pipe communicating therewith, a head carried by said pipe adjacent to said conduit, and one or more passages for permitting fluid from said conduit to pass by said head into said 70 pipe, substantially as described.

13. In a controller, the combination of a conduit, a longitudinally-movable outlet-pipe, said outlet-pipe having a head at or near its lower end, one or more ports for permitting 75 fluid to flow from said conduit into said outlet-pipe, and one or more ports above said head for the discharge of the fluid from said outlet-pipe, substantially as described.

14. In a controller, the combination of a 80 conduit, an outlet-pipe through which the fluid from the conduit passes, one or more ports for the discharge from said outlet-pipe of the fluid entering it from said conduit, and means operated by variation of the pressure 85 of the fluid in the conduit for varying the area of said ports inversely as compared with the pressure of the fluid in the conduit, substantially as described.

15. In a controller, the combination of a 90 conduit, a longitudinally-movable outlet-pipe communicating therewith, one or more ports for the discharge of fluid from said outlet-pipe, means operated by the pressure of the fluid for moving said pipe longitudinally, 95 and means operated by the fluid passing through the conduit for cushioning said outlet-pipe, substantially as described.

WILLIAM M. JEWELL.
